DESIGN FOR A CLOWN DOLL

Frances Kelcey and Cheri Rich, New York, N. Y.

Application April 12, 1940, Serial No. 91,636

Term of patent 7 years

To all whom it may concern:

Be it known that we Frances Kelcey and Cheri Rich, both citizens of the United States and residing at New York city, in the county and State of New York, have invented a new, original, and ornamental Design for a Clown Doll, of which the following is a specification, reference being had to the accompanying drawing, forming part thereof.

We claim:

The ornamental design for a clown doll, substantially as shown.

FRANCES KELCEY.
CHERI RICH.
